MULTIPLE SPRAYING DEVICE

Austin H. Downs, Glen Ridge, N. J., assignor, by
mesne assignments, to Roy F. Alder, Philadel-
phia, Pa.

Application June 17, 1938, Serial No. 279,613

10 Claims. (Cl. 299—58)

This invention relates to improvements in devices for spraying lacquers, varnishes, paints and more particularly to a device for spraying a mixture of coating materials.

A principal object of the invention is the provision of a trigger controlled pressure operated device which is self cleaning in that coating or spraying materials remaining on the nozzle after spraying has been stopped is automatically removed therefrom after the control trigger has been released by the operator.

A further object is the provision of such a device which is highly efficient in operation, simple and easily controlled to use a minimum amount of material and a minimum amount of air or gas pressure to accomplish the best atomizing and self cleaning results.

Still another object is the provision of a novel control system for the control of the atomizing gas pressure whereby gas, free of the spraying materials will continue to flow momentarily subsequent to the spray cut-off and to blow residual spray from the nozzles of the device.

Yet another object is the provision of a device whereby different spraying materials may be individually supplied to separate spraying nozzles and mixed externally of the spraying device on or just prior to being deposited on a surface.

A further object is the provision of means to individually control the quantity of spraying or coating fluid fed to each nozzle whereby the relative percentages of spraying materials may be regulated to meet particular needs.

Further objects include improvements in details of construction and are hereinafter set forth in full.

To the accomplishment of the foregoing and such other objects as may hereinafter appear, the invention consists in the novel construction, combination and arrangement of elements hereinafter described and then sought to be defined in the appended claims, reference being had to the accompanying drawings forming a part hereof and which show, merely for the purpose of illustrative disclosure, preferred embodiments of my invention, it being expressly understood, however, that various changes may be made in practice within the scope of the claims without digressing from the inventive idea.

In the accompanying drawings, in which similar reference characters denote corresponding parts:

Fig. 1 represents a perspective view of the novel spraying gun and associated control apparatus;

Fig. 2 is an enlarged vertical section illustrating in detail the automatic control mechanism for cutting off the supply of spray materials prior to the cut off of air or gas flow and for regulating the supply of spraying fluids individually; the line 2—2 of Fig. 1 lies in the plane of section which passes vertically and centrally through the cylinder 90 and through both material valves 71 and 72 in the block 43, and the section is viewed in the direction of the arrows;

Fig. 3 is an enlarged vertical section taken along line 3—3 of Fig. 2 and viewed in the direction of the arrows illustrating in detail the control mechanism for regulating the quantity of spraying material supplied to the spraying device;

Fig. 4 is an enlarged horizontal section of the spraying device or gun illustrating the air or gas distributing system therein; the line 4—4 of Fig. 1 lies on the plane of section which passes approximately centrally through the axis of the gun barrel and through both nozzles, and the section is viewed in the direction of the arrows;

Fig. 5 is a partial front elevation taken substantially along line 5—5 of Fig. 4 and viewed in the direction of the arrows;

Fig. 6 is a partial front elevation of a modified spraying device taken substantially along line 6—6 of Fig. 7, and viewed in the direction of the arrows; and

Fig. 7 is a partially sectionalized top plan view of the modified spraying device illustrated in Fig. 6.

Referring now to the drawings and first to Figs. 1, 4 and 5, the numeral 1 designates the body of a spraying device as a whole, this body including a barrel portion 2 and the handle portion 3, the handle portion extending downwardly from the barrel portion and inclined slightly to the rear so that the device has somewhat the appearance of an automatic revolver. The forward end of the device is provided with two outlet nozzles 5 and 5' arranged on a nozzle head 6 to slant toward each other so that the sprays ejected therefrom will converge and mix intimately at a focal point in front thereof.

Devices of this kind are employed to spray material principally, for example, in the manufacture of mirrors, one of the nozzles serving to spray silver nitrate solution and the other to spray a reagent to secure the silver nitrate coating to the back of a mirror. Other spraying materials may be used. The material for each nozzle is fed to the point of atomization by gravity, syphon or under pressure and consequently this device has

ports, passages and valves for controlling the admission and passage of the pressure fluid as well as the spraying liquids and the atomization of the same. A connection 7 to a suitable source of air or other fluid under pressure is made to the externally threaded nipple 8 on the lower end of the handle portion 3. Usually this pressure is automatically maintained by suitable regulating means as is well understood. This nipple 8 leads to a passage 9 which extends upwardly through the interior of the handle to the air inlet valve chamber 10 in the barrel portion of the device (Fig. 4). This valve chamber is provided with a valve seat 11 at the head of an air distributing chamber 12.

Slidably mounted in the barrel is a valve plunger 13 provided with a valve 14 in the valve chamber 10 which when resting on the valve seat 11 serves to cut off the pressure fluid from the source. A suitable spring 15 surrounding the plunger behind the valve 14 serves to force the valve on its said seat. The forward end of plunger 13 extends through the distributing chamber 12 and a suitable bearing opening in the wall of the barrel into a trigger recess or open slot 16. Therein a trigger 16' is pivotally supported from the barrel and the rear bearing face 16' thereof abuts the said plunger so that when the trigger is operated, the plunger 13 and consequently its valve 14 is moved away from its valve seat and permits fluid under pressure to enter the distributing chamber 12.

Barrel 2 is provided with two air passageways 17 and 18 which communicate with the distributing chamber through passageways 19 and 20. The nozzle head 6 which extends perpendicular to the barrel axis and is secured to the barrel by suitable set screws 21 or the like, has two passageways 23 and 24 which register respectively with the forward open ends of passageways 17 and 18. Passageways 23 and 24 communicate respectively with the upwardly extending passageways 25 and 26 and the latter in turn communicate respectively with the oppositely extending passageways 27 and 28. The latter communicate respectively with passageways 29 and 30 which lead to the atomizing chambers (not shown) of the nozzles 5 and 5'. These nozzles may be of any suitable type.

Below each nozzle 5 and 5', the nozzle head 6 is provided with the respective downwardly extending noses 31 and 32. These noses at their lower ends are provided respectively with the externally threaded nipples 33 and 34 to which the respective flexible tubes or hoses 35 and 36 are suitably attached.

The nipples and noses are respectively provided with upwardly extending passageways 37 and 38 which terminate respectively in the enlarged forwardly extending passageways 39 and 40 in the respective nozzles 5 and 5'. The latter passageways communicate with the atomizing chamber and nozzle tips (not shown) of any desired type and, for example, like those of the aforesaid application.

Material to be atomized and sprayed from the device is fed by gravity and in a controlled manner through the hoses 35 and 36. The latter are connected at their upper ends respectively to suitable nipples 41 and 42 extending from a valve block 43 (Figs. 1-3 inclusive) of a control device.

This valve block is provided along its bottom with the vertically extending bores 45 and 46, each threaded internally at their lower ends to thread-

edly receive and engage respectively the needle valve coupling nuts 47 and 48. These nuts are bored centrally at 49 and threaded to receive the respective needle valves 51 and 52 whose inner ends are pointed at 53 and 54 to close off the passageways 55 and 56 in the valve block 43 at the upper ends of bores 45 and 46. Suitable manipulating knobs 57 and 58 at the outer ends of the valves 51 and 52 facilitate the adjustment thereof and the variable restriction of the size of the opening into passageways 55 and 56 for a purpose hereinafter to be described. Suitable packings 57a surrounding the needle valves in enlarged portions 50 of the bores 48 are pressed into sealing relationship by the clamping nuts 59 and prevent leakage of liquid around the needle valves.

Nipples 41 and 42 communicate with the respective bores 45 and 46 through the respective passageways 60 (Figs. 1 and 3).

The valve block 43 is also provided with the vertically extending bores 61 and 62 whose lower ends communicate respectively with the passageways 55 and 56 leading to the bores 45 and 46. The upper ends of bores 61 and 62 are internally threaded at 63 and 64 to receive and threadedly engage respectively the plunger valve supporting nuts 65 and 66. The latter are each bored internally at 67 to receive slidably the respective slide valve rods 68 and 70. These rods at their lower inner ends are provided with enlarged heads 71 and 72 and each head is bored at its bottom 73 to receive a cushion-like valve 75 of soft rubber or the like which is adapted to seat over the top ends of the respective passageways 55 and 56. Each valve rod is surrounded in enlarged portion 68 of the bore 67 with packing material 71. This material is clamped by respective clamping nuts 79 and 80 to permit leak proof reciprocal motion of the valve rods 68 and 70.

The upper ends 81 and 82 of the valve rods are externally threaded to receive the double pairs of nuts 83, 84. A yoke or cross bar 85 is suitably perforated at opposite ends to receive the ends 45 of the rods. This yoke is clamped on each rod between the pairs of nuts 83, 84 and serves, when moved, to move said valve rods as a unit.

Automatic movement of the yoke 85 is effected as follows:

An upwardly extending piston rod 86 is suitably attached to the yoke 85 by the nuts 87. This rod extends through a bore 88 in a cylinder bracket 89 into a cylinder chamber 90. The chamber 90 is formed by providing a countersunk enlarged bore 91 in the upper face of the cylinder bracket 89 whose internal edge is threaded at 92 to engage a cylindrical hollow casing 93 threaded externally at 94 to engage said threaded edge 92. The upper end of the casing is also externally threaded to receive the cover or cap 95. Suitable packing 96 and a packing nut 97 permit leak-proof sliding motion of the piston rod.

An attaching nut 100 is attached to the threaded upper end of piston rod 86. This nut has an annular shoulder at 101 intermediate its ends, is threaded externally below said shoulder at 102 and has an upwardly extending annular flange 103 above said shoulder which defines a cylindrical space 104 for a purpose to be presently described. A backing washer 105 is adapted to be fitted over the threaded portion 102 and to abut the shoulder 101. A piston washer 106 of leather or other suitable soft material is also carried on 75 said threaded portion 102 below the backing

washer 105. Piston washer 106 is securely pressed against the washer 105 by a clamping nut 107 secured to nut 100 at 102 and having an annular flange 108 to maintain the major portion of washer 106 flat. The rim 109 of said washer 106 overhangs the flange 108 and extends downwardly so that air or gas under pressure forced into the cylinder chamber as will be presently described will press said rim firmly against the wall of the cylinder as the piston moves upwardly and prevent leakage around said washer 106 in well known manner.

A suitable strong coil spring 110 concentrically arranged about flange 103 and extending between the lower face of cap 95 and the upper face of washer 105 tends to urge the piston assembly comprising said two washers 105, 106 downwardly and as a result through piston rod 86 and yoke 85 tends to maintain the valves 75 closed on their seats above the respective passageways 55 and 56.

Upward movement of the piston assembly is limited variably by adjustable stop mechanism. In the present embodiment this comprises an externally threaded rod 111 which is adapted to screw into a threaded bore 95' in the cap 95. The lower end of rod 111 is provided with a nose or tip 112 which projects into the cylindrical space 104. The adjusted distance between the tip end 113 and the face of the nut 100 at the bottom of said space 104 determines the height to which the piston assembly may be raised in the cylinder 90. A lock nut 114 serves to lock the rod 111 in any adjusted position. A suitable manipulating knob 115 at the upper end of said rod 111 facilitates adjustment thereof.

Cylinder bracket 89 is provided with a nipple 120 suitably formed or attached thereto. This nipple connects with passageways 121 and 122 and the latter leads into the cylinder space 90.

Air or gas under pressure is supplied to the cylinder space 90 below the piston assembly from a gas reservoir 130 by a hose or pipe connection 131 attached to nipple 120 and to the outlet nipple 132 from said reservoir, said nipple communicating through a suitable passageway (not shown) with the chamber of said reservoir. An inlet nipple 133 also communicating with the chamber of said reservoir is connected to one end of a flexible hose or pipe 136. The other end of said hose is attached to a nipple 137 (Figs. 1 and 4) provided on the barrel 2 of the spraying device. This nipple communicates through a passageway 138 with a passageway 17 in said barrel. Thus some of the air or fluid under pressure flowing in passageway 17 when the trigger 16 is pressed will be diverted and led to the reservoir to build up a pressure therein sufficient to overcome the spring 110 in the cylinder chamber 90 for a purpose to be presently described. A suitable adjustable pressure relief valve 140 of any well known type is provided for the air reservoir to serve both as a safety valve and as a means of pressure regulation to compensate for variation in the strength of spring 110.

Spraying materials A and B respectively are supplied to the bores 61 and 62 from storage sources (not shown) located well above the height of the spraying device 1 in its normal position of use.

These sources are connected to nipples 150 on the valve block 43 by the flexible hoses or pipes 151 and 152. Each nipple leads to one of the bores 61 or 62 through a passageway 153. Thus, in the embodiment shown, material A is fed by

hose pipe or tube 151 to the bore 62 and material B is fed by hose pipe or tube 152 to bore 61. Opening of valve 75 in bore 61 permits material B to flow through passageway 55 into bore 45 and thence through tube or hose 36 to the atomizing chamber of nozzle 5. At the same time, opening of valve 75 in bore 62 permits material A to flow through passageway 56 into bore 46 and thence through tube or pipe 35 to the atomizing chamber of nozzle 5'. The feed of each material to the respective nozzles 5 and 5' is essentially a gravity feed controlled by the valves 75 and limited, as to quantity, by the respective needle valves 53 and 54.

For convenience, the valve block 43 and cylinder bracket 89 are rigidly interconnected by a connecting member 160 which latter has attached thereto a clamping or friction ring 161. This ring is adjustably carried on a supporting rod 162 extending vertically from a base 163. Likewise the reservoir 130, in the embodiment shown, is connected to and supported by the cylinder bracket 89.

In operation, the nozzles 5 and 5' of the spraying device are pointed at the work to be sprayed. The trigger 16' is pressed, opening valve 14 and permitting air or gas under pressure from the distributing chamber 12 to reach the atomizing chambers of the nozzles 5 and 5' through the respective sets of air passageways 19, 17, 23, 25, 27, 29 and 20, 18, 24, 26, 28, 30. At the same time some of the air from passageway 17 is diverted into passageway 138 and passes from there through nipple 137 and hose or pipe 136 to the reservoir 130 building up a pressure therein of sufficient magnitude to force air through nipple 132, tube 131, nipple 120 and passageways 122 and 121 into the cylinder chamber 90 and to move the piston assembly 105, 106 therein upwardly against the spring 110. Such movement automatically moves piston rod 86 and in consequence valve rods 69 and 70 upwardly, and moves valves 75 off their seats over passageways 55 and 56. This permits the needle valve controlled quantities of spraying materials to flow through tubes or hoses 35 and 36 to the spraying device and to reach the atomizing chambers of nozzles 5 and 5' through the respective sets of passageways 37, 39 and 38, 40. Spraying materials A and B are thoroughly atomized in the respective atomizing chambers of the respective nozzles 5 and 5' in well known manner and ejected as fine sprays which converge from the respective nozzles and become intimately mixed on or just before being deposited on the surface being sprayed.

When spraying is completed the trigger 16' is released. This closes the valve 14 and cuts off the main source of air supply from tube or hose 7. Air or gas in the reservoir 130 now begins to flow in reverse direction through the tube or hose 136 to passageways 138 and 17, from whence a portion of it flows directly to nozzle 5 and the balance flows through passageway 19 to distributing chamber 12, and passageway 20 to passageway 18 and thence to nozzle 5'.

As the pressure in the air reservoir recedes, the spring 110 overcomes the reduced pressure in cylinder space 90 and moves the piston and valve rod 86 downwardly closing the valves 75 and cutting off the spraying material supply. This cut-off occurs prior to reduction of the pressure in reservoir 130 to atmospheric level. The residual superatmospheric pressure in said reservoir after material cut-off continues momentarily to blow air or gas through the nozzles 5 and 5'. This

residual air or gas blowing after spraying material cut-off serves as a scouring blast to remove residual spraying materials from the nozzle tips before they have a chance to solidify and thus makes the spraying device self-cleaning.

It is to be noted that needle valves 53 and 54 are individually adjustable. Thus it is possible to individually regulate the respective quantities of spraying materials A and B and to make one any desired percentage of the other.

In Figs. 6 and 7 a modified form of spraying device is shown in which the percentage flow of spraying fluid to each nozzle may be individually controlled by structure directly embodied in the spraying device. Therein 201 designates the body of a spraying device as a whole, this body including a barrel portion 202 and a handle portion, the handle portion extending downwardly in the same manner as the handle portion 3 of Fig. 1. The forward end of the device is provided with two outlet nozzles 205, 205' arranged on a nozzle head 206 to slant toward each other so that the sprays ejected therefrom will converge and mix intimately at a focal point in front thereof.

Air or gas under pressure is led to the passageways 217 and 218 in the same manner as that shown in Fig. 4 and controlled by a trigger 216' operating a valve like valve 14 in the same manner as trigger 16' operates valve 14 of Fig. 4. Air or gas from the respective passageways 217 and 218 is led to the atomizing chambers (not shown) of the nozzles 205 and 205' through the respective sets of passageways 223, 225, 227, 229 and 224, 226, 228, 230 arranged in the same manner in the nozzle head 206 as the corresponding passageways 23, 25, 27, 29 and 24, 26, 28, 30 in the device of Fig. 4.

Below each nozzle 205 and 205', the nozzle head 206 is provided with the respective downwardly extending noses 231 and 232. These noses are internally bored to provide passageways 231' and 232' and threaded to receive respectively the nipples 232 and 233, to which in turn the flexible tubes or hoses 235 and 236 are suitably attached.

Each passageway 231' and 232' leads to a horizontally disposed bore 237 in the nozzle head 206, one adjacent and behind each of said nozzles 205, 205'. Each bore is internally threaded for its entire length and has a valve seat nut 238 screwed into it and lying at its inner end. This nut has a central bore 239 countersunk at its ends 239' and 239'' with the end 239'' serving as a valve seat. A combination needle valve and closure valve device adapted to vary adjustably the size of passageway 239 and to serve as a cut-off is provided for each nut 238. These combination valve devices each comprise a valve rod 240 provided at its inner end with a reduced diameter needle valve 241. Adjacent said needle valve on a reduced portion 242 of each rod, a flat valve 243 is mounted. This flat valve has an inset 244 of soft material, such as rubber or the like so as measured in diameter as to close the countersunk portion 239'' of the passageway 239 when it rests on the valve seat thereof. Each valve rod 240 extends through a bearing surface 245 of a supporting nut 246 screwed into each of the bores 237. Suitable packing material 247 arranged in an enlarged portion 248 of each of the bearing surfaces 245 and clamped into position by clamping nuts 249 serves to permit leak-proof reciprocal sliding motion of the valve rods 240.

The valve rods 240 extend rearwardly from the clamping nuts 249 and are each provided with a pair of spaced abutments or collar members

250 which have their opposite inner faces curved at 251.

A yoke member 252 having tines 253 at its opposite ends extends between the valve rods and the tines engage between the respective pairs of abutments 250. The side edges 253' of the tines are likewise curved to permit rotation of the yoke member relative to the valve rods. The yoke member has a rearwardly projecting centrally located flange 254. This flange at its rear end has a slot 255 into which a portion of the trigger 216' extends. The flange has laterally oppositely projecting noses 257 which engage the trigger so that movement of the latter causes corresponding movement of the yoke member 252.

A pair of oppositely extending flanges 260 on the barrel 202 project beyond the axes of the respective valve rods 240. Each flange is provided with an adjusting screw 261 and lock nut 262. These screws are arranged in axial alignment with the respective valve rods and permit individual adjustment of each valve rod 240 and consequently the needle valves 241 at their inner ends. Since abutments 250 and the tines 253 have curved edges, the yoke member 252 is capable of rotation in conformity with the relative adjustment of the individual valve rods.

In operation hoses 235 and 236 are connected to sources of materials A and B located well above the positions of use of the device. When the trigger 216' is squeezed air valve 214 is opened admitting air or gas under pressure through the various sets of passageways described to the atomizing chamber of each nozzle 205 and 205'. Simultaneously the trigger moves the yoke member 252 rearwardly causing the flat valves 243 to be lifted off their respective seats 239' and permitting the spraying materials A and B to flow past the needle valves 241 to the respective nozzles 205 and 205' through the passageways 239. One spraying material only is delivered to the atomizing chamber of each nozzle from the respective passageway 239 through the respective passageways 270. In the atomizing chambers the air under pressure mixes with and atomizes the particular spraying material. The atomized spray from each nozzle is ejected therefrom and converges to mix intimately with the spray from the other nozzle on or just before reaching the surface being sprayed.

When the trigger 216' is released, the air valve 214 and the flat valves 243 simultaneously cut off the fluid pressure and the supply of spraying materials.

If desired, this modified form of spraying device can be connected with the valve block and reservoir 130. Hoses or tubes 235 and 236 are connected to the respective nipples 41 and 42 of said block and hose 130 is connected to a nipple 60 which can be attached to the barrel 202 and leading to passageway 338 therein connecting with passageway 217. Operation when the trigger 216' is now pulled is the same as the operation of the device of Fig. 4. The clean out blast from residual gas in the reservoir drives off residual spraying fluid from the two nozzles 205 and 205'. The use of the valve block and air reservoir with this latter device is optional. When not used, passageway 338 is closed off by a removable plug 339.

Since the needle valves 241 are individually controllable, the relative percentages of spraying materials A and B can be individually regulated to anything desired by the operator.

It is to be understood of course that the de-

vices may be modified as to details of construction without departing from the spirit of the invention and that modifications are contemplated within the scope of the appended claims.

What is claimed is:

1. In spraying apparatus, a spraying device having a nozzle, means for permitting passage of spraying material to said nozzle, means for atomizing said material at said nozzle including a gas passageway in one part of said device, a gas distributing chamber connected with said passageway and gas passageways leading from said chamber to said nozzle, valve means for controlling the entrance of gas into said chamber and means associated with said device and connected to said last named gas passageway for cutting off the said spraying material to said nozzle prior to cessation of flow of gas thereto, said last named means comprising a gas reservoir and valve cut-off means for said spraying material responsive to pressure of gas in said reservoir.

2. In spraying apparatus, a spraying device having nozzles thereon adapted to emit converging sprays, means for permitting passage of a different spraying material to each nozzle, means for atomizing said different materials at each nozzle, including a gas passageway in one part of said device, a gas distributing chamber connected with said passageway and gas passageways leading from said chamber to said nozzles, valve means for controlling the entrance of gas into said chamber, and means associated with said device and connected to one of said last named gas passageways for cutting off the supply of said spraying materials to said nozzles prior to cessation of flow of gas thereto, said last named means comprising a gas reservoir and valve cut-off means for said spraying materials responsive to pressure of gas in said reservoir.

3. In spraying apparatus having means to supply gas under pressure and spraying material to an atomizing nozzle, means to cut-off the supply of spraying material prior to cessation of gas flow through the said nozzle whereby residual spraying material on said nozzle is removed by gas after cut-off of said material, said last-named means including a gas reservoir, and a cut-off valve for said material operated by pressure of gas in said reservoir.

4. In spraying apparatus having means to supply gas under pressure and spraying material to an atomizing nozzle, means to cut-off the supply of spraying material prior to cessation of gas flow through the said nozzle whereby residual spraying material on said nozzle is removed by gas after cut-off of said material, said last-named means including a gas reservoir, and a cut-off valve for said material operated by pressure of gas in said reservoir, and a piston connected with said valve and operated by pressure of gas in said reservoir.

5. In spraying apparatus having means to supply gas under pressure and spraying material to an atomizing nozzle, means to cut-off the supply of spraying material prior to cessation of gas flow through the said nozzle whereby residual spraying material on said nozzle is removed by gas after cut-off of said material, said last-named means including a gas reservoir, and a cut-off valve for said material operated by pressure of gas in said reservoir, a piston connected with said valve and operated by pressure of gas in said reservoir, means for connecting said reservoir to the gas supply of said device and means for con-

nnecting said cut-off valve in the material supply to said device.

6. A spraying device having a nozzle, means for permitting passage of spraying material to said nozzle, means for regulating the quantity of spraying material passing to said nozzle, valve means for closing off the passage of spraying material to said nozzle, means for atomizing said material at said nozzle including a gas passageway in one part of said device, a gas distributing chamber connected with said passageway, and a gas passageway leading from said chamber to said nozzle, valve means for controlling the entrance of said gas to said chamber and means for simultaneously operating said two valve means to open position, and means associated with said device and responsive to gas pressure for cutting off the supply of said spraying material to said spraying device prior to the cessation of flow of gas to said nozzle.

7. In a spraying device having a nozzle, means for permitting passage of spraying material to said nozzle, means for regulating the quantity of spraying material passing to said nozzle, valve means for closing off the passage of spraying material to said nozzle, means for atomizing said material at said nozzle including gas passageways leading to the nozzle, valve means for controlling the entrance of gas to said passageways, means for simultaneously operating said two valve means to open position, and means associated with said device and responsive to gas pressure for cutting off the supply of said spraying material to said spraying device prior to the cessation of flow of gas to said nozzle.

8. In a spraying device having nozzles thereon adapted to emit converging sprays, means for permitting passage of a different spraying material to each nozzle, means for individually regulating the quantity of spraying material passing to each nozzle, valve means for closing off the passage of spraying materials to said nozzles, means for atomizing said materials at said nozzles including a gas passageway in one part of said device, a gas distributing chamber connected with said passageway and gas passageways leading from said chamber to said nozzles, valve means for controlling the entrance of gas to said chamber, means for simultaneously operating both of said valve means to open position, and means responsive to gas pressure for cutting off the supply of said spraying material to said spraying device prior to the cessation of flow of gas to said nozzles.

55 9. In a spraying device having a nozzle, means for permitting passage of spraying material to said nozzle, a combination valve device including an adjustable needle valve for regulating the quantity of spraying material passing to said nozzle, and a second valve surrounding said needle valve for closing off the passage of spraying material to said nozzle, means for atomizing said material at said nozzle including a gas passageway in one part of said device, a gas distributing chamber connected with said passageway and gas passageways leading from said chamber to said nozzle, a valve for controlling the entrance of gas to said chamber, trigger operated means for simultaneously operating said last-named valve and said second valve to open position, and means associated with said device and responsive to gas pressure for cutting off the supply of said spraying material to said spraying device prior to the cessation of flow of gas to said nozzle.

60 10. In a spraying device having nozzles there-

on adapted to emit converging sprays, means for permitting passage of a different spraying material to each nozzle, combination valve devices comprising closure valves for closing off the passages of spraying material to each nozzle and a needle valve associated with each closure valve and movable therewith, adjustable means for limiting the movement of each of said combination valve devices in one direction to individually regulate the quantity of spraying material passing to each nozzle, means for atomizing said materials at said nozzles including a gas passageway in one part of said device, a gas distributing chamber connected with said

5 passageway and gas passageways leading from said chamber to said nozzles, a valve for controlling the entrance of gas to said chamber, means for simultaneously operating said last-named valve and said combination valve devices to open position, a swingably mounted connection between said operating means and said combination valve devices to permit a different degree of movement of each valve device, and means associated with said device and responsive to gas pressure for cutting off the supply of said spraying material to said spraying device prior to the cessation of flow of gas to said nozzles.

10 AUSTIN H. DOWNS.
